UNITED STATES PATENT OFFICE.

AUGUST CARLEWITZ, OF NEWARK, NEW JERSEY.

DESIGN FOR A CORNICE.

SPECIFICATION forming part of Design No. 21,731, dated July 19, 1892.

Application filed May 6, 1892. Serial No. 432,082. Term of patent 7 years.

To all whom it may concern:

Be it known that I, AUGUST CARLEWITZ, a citizen of the United States, residing at the city of Newark, in the county of Essex and State of New Jersey, have invented and produced a new and original Design for a Cornice to be used in the angle formed by the wall and ceiling of a room, of which the following is a specification, reference being had to the accompanying drawings, showing a part thereof.

Figure 1 is a front elevation of the cornice, showing my design. Fig. 2 is a cross-section through the line *a a* of the same. These views are deemed necessary to fully illustrate my design.

The prominent feature of my design consists in a raised figured surface, the outlines of which when viewed in elevation, as in Fig. 1, will lie principally within the cove of the cornice, but also at one point extending over the upper and lower moldings thereof.

A is the cove of the cornice, which is concave in form, and B C are respectively the upper and lower beads or moldings.

The central feature of the design consists of the stem or vine V, extending along the cove and across the same from top to bottom. Branching from the stem V are the large conventional leaves D D, which lie within the limits of the cove. There is also a branch F, which leaves the main stem and terminates in a flower on the lower molding. The branch E does not extend outside the limits of the cove. On the upper molding is a seed-pod G at the end of a tendril connected with the main stem.

What I claim as new is—

The design for a cornice herein shown and described, the same comprising the upper and lower plain moldings B and C and the intervening cove A, with raised stem and leaves, substantially as shown and described.

AUGUST CARLEWITZ.
